[75] Inventor: **Jules Schneider**, Colts Neck, N.J.

Primary Examiner—Doris V. Coles
Attorney, Agent, or Firm—Kenyon & Kenyon

[73] Assignee: **Aerogroup International, Inc.**, Edison, N.J.

[57] CLAIM

[**] Term: 14 Years

The ornamental design for surface ornamentation for a shoe sole, as shown and described.

[21] Appl. No.: **62,571**

DESCRIPTION

[22] Filed: **Nov. 19, 1996**

FIG. 1 is a bottom plan view of surface ornamentation for a shoe sole showing my new design.

[51] LOC (6) Cl. **02-04**

The broken line showing of the rest of a shoe sole is for illustrative purposes only and forms no part of the claimed design.

[52] U.S. Cl. **D2/951**
